UNITED STATES PATENT OFFICE.

WALTER G. STOUT, OF CAMDEN, NEW JERSEY, AND HIRAM O. COWDRICK,
OF PHILADELPHIA, PENNSYLVANIA.

TOOTH-BRUSH.

SPECIFICATION forming part of Letters Patent No. 540,884, dated June 11, 1895.

Application filed November 2, 1893. Serial No. 489,805. (No model.)

To all whom it may concern:

Be it known that we, WALTER G. STOUT, residing in the city and county of Camden, State of New Jersey, and HIRAM O. COWDRICK, a resident of the city and county of Philadelphia, State of Pennsylvania, citizens of the United States, have invented a new and useful Improvement in Tooth-Brushes, which improvement is fully set forth in the following specification and accompanying drawings.

Our invention consists of a tooth brush formed of a handle having a reservoir therein for tooth-wash or fluid, a nozzle for directing the latter to the head of the brush, means for permitting the supply and preventing the escape of the fluid, and a removable head which provides access to the nozzle, so that the same may be closed when the reservoir is to be replenished, and permits the substitution of fresh bristles or a rubbing portion when the latter is worn out, the construction and operation of parts being hereinafter more fully set forth.

Figure 1 represents a side elevation of a tooth-brush embodying our invention. Fig. 2 represents a longitudinal sectional view thereof. Fig. 3 represents a face view thereof, the head of the brush being removed. Fig. 4 represents a transverse section on line $\alpha\alpha$, Fig. 1.

Similar letters of reference indicate corresponding parts in the several figures.

Referring to the drawings, A designates the handle of the brush, and B designates the back of the rubbing portion thereof, said back being open and having flanges C on its sides to receive and hold the head D of the bristles or rubbing portion, said head as is evident being removable from said back.

The handle is hollow forming a reservoir, and terminating on its inner end in a nozzle E, which is in line with the face of the head D, and has its discharge end at the inner end of the back B, so as to direct the flow of the wash across the face of the said head D.

On the outer end of the handle is a screw plug or cap F, which closes said end, for preventing the escape of the tooth-wash or fluid thereat. In the side of the handle, near said

outer end is an air vent G, which when the plug F is in position, closes said vent, and prevents the entrance of air into the handle.

The handle, back with flanges, and nozzle are preferably formed of a single piece of any suitable material.

55

The operation is as follows: The head D, and the plug or cap F are removed, and one of the fingers pressed against the discharge end of the nozzle, after which the handle is filled or supplied with tooth-wash. The plug is then restored, whereby the vent and the end of the handle are closed, the head being also replaced. When the brush is to be used, the plug is removed sufficiently to uncover the vent, whereby the wash will flow through the nozzle across the face of the back D and supply the bristles or rubbing portion with the wash. When service of the brush is no longer required the plug is operated to close the vent, when the supply of wash ceases, and improper escape of the same is prevented.

When the bristles or rubbing portion wear out, the head may be withdrawn and substituted by a fresh one with bristles or portion, and the brush render service as before, the head sliding on the back between the flanges C, both in removal and reapplication.

It will be noticed that the nozzle does not pass through either of the backs B or D, but its discharge end is at one end of the face of the back D, so that the flow is across the said face, and not through said head, which latter is imperforated or solid whereby the wash is thoroughly distributed to all of the bristles. This construction not weakening the backs by having openings therein, furnishes a more durable article.

Having thus described our invention, what we claim as new, and desire to secure by Letters Patent, is—

90

As a new article of manufacture, a tooth brush consisting of a hollow handle, a nozzle, and a back with side flanges formed of a single piece of material, a detachable head fitting in said flanges, and a plug closing the inlet of the handle, the discharge end of the nozzle being at the inner end of the brush, said parts being combined substantially as described.
